UNITED STATES PATENT OFFICE

RUDOLF BRUNE, OF DORTMUND, GERMANY

CORE-PEELING DEVICE FOR FOUNDRIES

Application filed October 23, 1926, Serial No. 143,722, and in Germany October 29, 1925.

This invention has reference to means for the trimming, peeling or shelling of sand cores for casting purposes, and it is one of the important objects of my invention, to devise means of facilitating this operation and to secure exact shapes and reliable results irrespective of the shape of the cores to be treated. The means heretofore employed for manufacturing foundry cores do not admit 10 of the manufacture of cores of all required sizes, it being particularly difficult to obtain comparatively thick and long cores and cores of varying cross sections with the means suggested by the previous art. It is however a 15 point of great importance in the case of the operation of foundries according to modern methods to be able to obtain not only relatively elongated, but also comparatively thick cores, and cores of three-cornered, four-cornered, six-cornered, oval or other cross sectional shapes, and this object is realized by the means set forth in the invention to be described hereinafter.

The invention is shown by way of exemplification in a preferred embodiment in Figure 1 of the drawing in vertical section and in Figure 2 in plan view. Figures 3 and 4 are illustrations of a peeling or trimming device for a hexagonal core, shown respectively in 30 vertical section and in plan view. Figures 5 and 6 are representations of details showing respectively cutting knives with substantially square and rectangular shapes and with rounded edges.

Upon the foundation or foot 1 which may be hollowed out or provided with holes with a view of reduction of weight the standards or connecting bolts 2 are disposed upon which the sand chest or bin 3 is mounted which latter at its front side is provided with a recessed, flattened or concaved portion 5 to accommodate the operator. At this part of the device a crank handle 6 may be provided adapted to actuate a sprocket wheel 8 by 40 means of a shaft 7 from which by means of the downwardly extending chain 9 and sprocket wheel 10 the lower shaft 11 and the small gear wheel 12 are rotated. This gear wheel 12 meshes with the rack bar 13 which 45 also acts as a lifting and cam-bar. At its lower portion the bar 13 is guided in the bearing 14 and its upper portion is provided with a piston or plunger 15 upon which a wooden plate or the like 16 is mounted. This plate is intended to prevent injuring the peeling or 55 trimming knife 17 by the iron piston or plunger 15 and to entirely force the core through the trimming or peeling knife. The said cutting, trimming or peeling instrumentality 17 is disposed in the upper part of the device in a casing 18 which is mounted upon the conical core-tube 22 by bayonet joint or the like. The oblong discs 20 which are fastened to the trimming or peeling instrumentality 18 by means of the small screws 19 60 admit of the ready loosening of the peeling or trimming knives and of the replacing thereof by a smaller or larger or differently shaped knife in accordance with the core to be produced. The core-tube or sleeve 22 may 65 likewise be connected by bayonet-joint to the foundation or foot 1 and at its upper portion to the plate 23, which latter may be secured to the plate of the sand box 3 together with the peeling or trimming instrumentality by 70 a bayonet joint or the like 24. Instead of bayonet joint screw-threaded connection may be employed. The core sleeve 22 is of some- 75 what reduced diameter at its lower end so as to be flaring upwards. This feature is of im- 80 portance, inasmuch as by this means the friction of the core-material against the walls which is particularly great in the case of sand and similar core-material is reduced, adhe- 85 sion to the walls is prevented and the integ- 90 rity of the core is preserved. The diameter of the plunger 15, 16 which is not a compressing, but merely a supporting plunger corre- 95 sponds to the narrower part of the containing tube 22, so as to eliminate friction and jerk- 100 ing movement. In Figure 1 of the drawing the plunger members 15, 16 are indicated in dotted lines in their lowermost position, and in full lines in their raised operative position in which the plunger-members 15, 16 are out of contact with the walls of the container. The way of the chain 9 is indicated in broken lines.

The trimming or peeling knife 17 may assume different polygonal shapes; as shown in 100

Figures 3 and 4 at 25, it may be substantially hexagonal; or it may be substantially square or four-cornered, as shown at 26 in Figure 5; or it may be of oblong rectangular shape 27 according to Figure 6. But it should be understood that by correspondingly changing the configuration of the peeling or trimming knife any desired suitable shape of core may be obtained.

- 10 In order to provide a shoulder or a stem on the cores, which is often required, the trimming or peeling instrumentality 18 may be provided with a projection or shoulder at its outer periphery 28 upon which shoulder 15 a split ring 29 with two handles 30 may be rotatably mounted. Upon this ring a knife 31 is disposed in a dove-tailed groove or the like, so that by manipulating the handles 30 and rotating the ring the knife 31 will scrape off or cut out the shouldered or stem-shaped portion at the head of the core. Evidently it is also possible to provide corresponding grooves by turning at any suitable places of the core.
- 20 25 In accordance with the desired sizes and shapes of the cores the corresponding knives 17 and the corresponding core sleeves 22 are inserted. For the reception of the rack bar or lifting bar 13 a tube 32 is provided below the foot in the ground.

30 After the rack bar 13 has been fully lowered by rotating the crank handle and the sprocket wheel 8, the core tube or sleeve 22 is filled with the foundry sand which is packed and pounded by hand; then the rack bar 13 with the piston 15 and the wooden plate 16 are raised, until the core has been trimmed off and peeled by the knife 17. The laterally dropping off core sand may be pushed into the sand box 3 and may be used for the building of the next core.

35 Inasmuch as the core-material, particularly sand or the like, must be protected and preserved against any deformation, bending, expansion, change of volume, and undue tension, it is obvious that the various devices employed for the forcing of a stream of clay or similar plastic material through a die member cannot be employed for the purposes of this invention, nor for the surface-treatment of foundry-cores generally, inasmuch as they all impose a very injurious strain on the material, and put it under a rather heavy 40 compressing pressure, aside from the additional very serious drawback that in most of the devices for the treatment of a stream of clay or other plastic material this material is fed horizontally either insufficiently supported, and thereby subject to friction, or even not supported at all, so as to be open to bending and deformation. Of course, all such difficulties militate against the purpose of exactness, precision and unchangeability 45 which are conditions of paramount impor-

tance for the patterns for which the core is intended.

While I have described my invention in certain particular embodiments it should be understood that modifications may be made in the shape and arrangement of parts, and that no limitations on the invention are intended other than those imposed by the scope of the appended claims.

I claim:—

1. Trimming and smoothing device for foundry-cores comprising in combination, a substantially vertically disposed, and upwardly widening tubular member, a plunger axially movable in said member and corresponding to the smaller diameter thereof, and trimming means, marginally disposed at the wider end of said member.

2. Trimming and smoothing device for foundry cores comprising in combination, a substantially vertically disposed, upwardly gently widening tubular containing member, a supporting plunger corresponding to the smaller diameter of said member and movable axially thereof, and adapted to support a foundry-core, and trimming means, marginally disposed at the wider part of said member, and engageable with the foundry-core.

3. Trimming and smoothing device for foundry-cores comprising in combination, a base, a substantially trough-shaped head, spacedly superimposed with relation thereto, a substantially vertically disposed, upwardly widening tubular containing member intermediate the head and the base and detachably secured to them, a supporting plunger in said member corresponding to the smaller diameter thereof, and axially movable therein, and adapted to removably support a foundry-core, marginally arranged trimming knives at the wider part of said member, engageable with the foundry core, and operating means for the plunger.

4. Trimming and smoothing device for foundry-cores comprising in combination, a substantially vertically disposed, upwardly widening tubular containing member, a plunger axially movable in said member and corresponding to the diameter of the narrower part thereof and adapted to support a removable foundry-core, marginally disposed trimming knives for said core at the wider part of said tubular member, and additional rotatable trimming means for said core mounted at said wider part.

5. Trimming and smoothing device for foundry-cores comprising in combination, a substantially vertically disposed, upwardly widening tubular containing member, a plunger, axially movable in said member and corresponding to the diameter of the narrower part thereof, and adapted to removably support a foundry-core, marginally disposed trimming knives at the wider part of the tubular member and engageable with the core, ad-

ditional movable knives at said wider part, engageable with the core out of the plane of the trimming knives.

6. Trimming and smoothing device for foundry-cores comprising in combination, a substantially vertically disposed, upwardly widening tubular containing member, a plunger axially movable in said member and corresponding to the diameter of the narrower part thereof, adapted to support a charge of core-material, marginally disposed trimming and shaping knives at the wider part of the tubular member, and means to move the plunger with the charge thereon and the knives into and out of engaging contact with each other.

In witness whereof I affix my signature.
RUDOLF BRUNE.
